UNITED STATES PATENT OFFICE.

OSCAR LEISTNER, OF CHICAGO, ILLINOIS.

DESIGN FOR A BASKET.

52,484.

Specification for Design. Patented Sept. 24, 1918.

Application filed June 10, 1918. Serial No. 239,334. Term of patent 7 years.

To all whom it may concern:

Be it known that I, OSCAR LEISTNER, citizen of the United States, residing at Chicago, in the county of Cook and State of Illinois, have invented a new, original, and ornamental Design for a Basket, of which the following is a specification, reference being had to the accompanying drawing, forming a part hereof.

This invention has for its object to provide a novel and ornamental design for a basket.

The accompanying drawing illustrating my design shows a perspective view of a basket embodying the invention.

I claim:

The ornamental design for a basket substantially as shown.

OSCAR LEISTNER.

Witnesses:

THEO. KIRCHEN,
ADOLPH HARLES.
